UNITED STATES PATENT OFFICE

137,549

DESIGN FOR A CONTAINER FOR COSMETICS OR SIMILAR ARTICLES

Jon Stengren, Forest Hills, N. Y., assignor to Milkmaid Inc., New York, N. Y., a corporation of New Jersey

Application July 21, 1943, Serial No. 110,725

Term of patent 3½ years

(Cl. D58—11)

To all whom it may concern:

Be it known that I, Jon Stengren, a citizen of the United States of America, residing in Forest Hills, Long Island, county of Queens and State of New York, have invented a new, original, and ornamental Design for a Container for Cosmetics or Similar Articles, of which the following is a specification, reference being had to the accompanying drawings, forming a part thereof.

In the drawings:

Figure 1 is a perspective view of a container for cosmetics or similar articles embodying my new design.

I claim:

The ornamental design for a container for cosmetics or similar articles, as shown.

JON STENGREN.
